UNITED STATES PATENT OFFICE.

ARIZONA Z. COATS, OF NEWBERN, TENNESSEE, ASSIGNOR OF ONE-HALF TO ELMER HEADDEN, OF NEWBERN, TENNESSEE.

SOUND BOX.

Application filed October 11, 1921. Serial No. 506,954.

To all whom it may concern:

Be it known that I, ARIZONA Z. COATS, a citizen of the United States, residing at Newbern, in the county of Dyer and State 5 of Tennessee, have invented certain new and useful Improvements in a Sound Box, of which the following is a specification.

This invention relates to sound boxes for phonographs and the primary object thereof is to provide a device which will amplify the sound without distorting the sound waves and which will eliminate the emission of scratchy and grinding sounds common to sound boxes of the diaphragm and 15 reproducing needle type.

Another object is to provide simple and efficient means to effect a duplication of the sound vibration produced by a single stylus or needle and to so encase the diaphragms 20 that they are protected from the accumulation of dust thereon and consequent deadening of the sound.

With these and other objects in view, the invention consists in certain novel features 25 of construction as hereinafter shown and described and then specifically pointed out in the claim, and in the drawings illustrative of the preferred embodiment of the invention.

30 In the accompanying drawings:—

Figure 1 represents a side elevation of a tone arm equipped with this improved sound box.

Fig. 2 is an edge view or front elevation 35 thereof with the tone arm broken off.

Fig. 3 is a central vertical section taken on the line 3—3 of Fig. 1.

Fig. 4 is a side elevation of one section 40 of the sound box taken from the inner face thereof with parts in section.

Fig. 5 is an enlarged transverse section taken on the line 5—5 of Fig. 1.

Fig. 6 is a side elevation taken from the inner face of one section of the sound box 45 with the diaphragm removed.

Fig. 7 is a detail perspective view of the ring which is located between the diaphragms.

In the embodiment illustrated the sound 50 box 1 constituting this invention is composed of two sections 2 and 3 here shown circular in configuration although not necessarily so and which are provided at their meeting edges with apertured ears or lugs 55 4 those on one section registering with those

on the other to receive the connecting bolts or screws for uniting the sections. Any desired number of these lugs may be employed four being here shown. These sections 2 and 3 are exactly alike being each 60 provided on its inner face with a packing receiving groove 5 adjacent the perimeter thereof and with a centrally disposed aperture 6, pipes 7 being formed as a part of said sections around the openings 6 as is 65 shown clearly in Fig. 3 and which are designed to conduct the sounds from the sound box to the tone arm shown at T through means presently to be described.

Arranged within the seat 5 in sections 2 70 and 3 are packings 8 on which are designed to be supported the diaphragms 9 and 10. These diaphragms 9 and 10 are held in spaced relation by a ring 11 composed of any suitable metal and provided on its opposed face with rubber rings 12 designed to contact with the opposed faces of the diaphragms and hold them in spaced relation and out of contact with the metal. The sections 2 and 3 of the sound box are provided at their meeting edges at a point opposite the connections of the sound box with the tone arm with an opening 13 equipped with a collar 14 and in which is designed to be mounted a needle holder 15. This needle 80 holder 15 is held pivotally mounted in the opening 13 by oppositely disposed set screws 16 as is shown clearly in Fig. 5.

The connection between the top of the needle holder or arm 15 and the two diaphragms whereby the vibratory movement of the needle produced by the record is transmitted to the diaphragms must be flexible and non-rigid, and also elastic to the extent of causing pulsations of the diaphragms, in response to the vibratory movements of the needle, without alternating the normal direction of such pulsation movements, that is to say in order that the diaphragm, caused to pulsate by vibrations imparted to it, shall have normal pulsating movement unrestrained by the character of the connection employed to effect the pulsations. For this purpose two flexible sound bars 17 and 18 are here shown connected at 90 one end with the upper portion of the needle holder 15 and at their other end with the diaphragms 9 and 10 at their centers, said bars being shown parallel throughout the greater portion of their length. By em- 100 110

ploying this two part sound bar connecting the upper end of the needle holder with the two diaphragms each vibration of the needle will be communicated simultaneously 5 to the two diaphragms through these duplicate sound bars thus producing like sound waves by like pulsations of the two diaphragms.

The sound conducting tubes 7 are connected 10 at their free ends with the tone arm T by a substantially inverted Y-shaped tubular member 19, the arms 20 and 21 of which telescopically engage the ends of the tubes 7 and are snugly fitted thereto being 15 connected by screws or otherwise while the shank or stem 22 is rotatively connected with the tone arm, said shank having a peripheral slot 23 therein for this purpose through which extends a stud 24 carried by 20 the tone arm as is shown clearly in Fig. 1.

From the above description it will be obvious that a sound box constructed as hereinafter shown and described having the two diaphragms connected with the needle 25 holder receiving simultaneously the vibrations therefrom will not only protect the diaphragms from the accumulation of dust thereon and the deadening of the sound incident to such accumulation but the sound 30 from each diaphragm will be independently carried off through the tube 7, and mingled in the tone arm at a point remote from the

diaphragm, thus amplifying the sound without in any way distorting the sound waves. This encasing of the diaphragms in 35 the sound box also entirely eliminates the emission of scratchy and grinding sounds which are common to sound boxes of the diaphragm and reproducing needle type.

The preferred embodiment of the invention is disclosed in the drawings and set forth in the specification, but it will be understood that any modifications within the scope of the claimed invention may be made in the construction without departing from 40 the principle of the invention or sacrificing any of its advantages.

What I claim is:—

A sound box of the class described composed of a cylindrical body the ends of 50 which are equipped each with a sound conveying tube said body being constructed of detachably connected sections, a diaphragm mounted in each of said sections, a spacing ring arranged between said diaphragms, said ring being split and the ends thereof spaced apart, a sound arm extending through the opening in said ring and engaged with said diaphragms, and a needle holder connected with said sound arm. 55

In testimony whereof, I affix my signature hereto.

ARIZONA Z. COATS.
